UNITED STATES PATENT OFFICE.

WILLIAM H. BERRY, OF CHESTER, PENNSYLVANIA.

FEED-WATER REGULATOR.

1,340,365.

Specification of Letters Patent.

Patented May 18, 1920.

Application filed March 25, 1916. Serial No. 86,782.

To all whom it may concern:

Be it known that I, WILLIAM H. BERRY, a citizen of the United States, residing at Chester, in the county of Delaware and State 5 of Pennsylvania, have invented new and useful Improvements in Feed-Water Regulators, of which the following is a specification.

My invention relates to an improvement 10 in feed water regulators for steam boilers or other vessels in which the automatic maintenance of the level of the water or other liquid is desired, or in which an alarm is to be sounded to warn the attendant in case of 15 an undue variation in the level.

The present invention is an improvement upon a former invention covered by Patent No. 726,792, granted to me April 28, 1903, and has for its object the providing of separate mechanism for operating the feed control and the alarm whistle, so that they each 20 may be independently adjusted or removed for repairs. It also relates to certain details of construction indicated in the accompanying drawings and specifications.

I have shown two forms of the invention, the principal one of which is designed to permit a wide divergence of the liquid level between the alarms, and the other for use 30 where the divergence may be slight.

In the drawings, Figure 1 is a sectional elevation of the device intended to take the place of the usual water column, and allow a wide divergence between the alarms. Fig. 35 2 is a vertical section of certain valve mechanism taken on the line $x-x$ of Fig. 3. Fig. 3 is a vertical section of the same on the line $y-y$ of Fig. 2. Fig. 4 is an elevation of a shortened vessel secured to the side of the 40 ordinary water column of a boiler. This may be attached directly to the boiler or other vessel to be controlled, the only difference being that a wide divergence between the alarms can not be obtained with 45 the device in this form. Fig. 5 shows details of construction hereinafter referred to.

Similar numerals designate similar parts in the various figures.

1 represents a water column of the usual 50 type provided with try cocks, etc., and further with internal ribs 20 which keep the elongated float 5 in vertical position without undue friction, and prevent it from swinging against the try cock openings. 55 The column 1 has an offset portion 3, placed well above the high water line, and

opening into the column through an inclosed space 4, through which the members 6 and 7 convey motion from the float 5 to the rotary or oscillating member 8.

Attached by suitable bolts to one side of the offset portion 3 is a fixture 10. This fixture is provided with a projection 9 reaching into the space 4, and a removable cover 15 inclosing a chamber 14.

The projection 9 is furnished with a passage 41 connecting the chamber 14 with the space 4, and is adapted to receive the member 8 in such manner as to allow it to rotate or oscillate therein, and also move endwise sufficiently to open and close the passage 41 by means of the valve face 13 of said member and the seat 12 formed near the inner end of said passage 41.

The member 8 may be of varied character, 75 but I show it as consisting of a flat bar having a circular flange 8² upon which is the check valve face 13, and a flange 8³ turned to fit the bore or passage 41. The steam or other fluid is allowed free course through 80 this passage 41 by means of notches 8⁴ cut in the outer part of the flange 8² and through holes 8⁵ in the flange 8³. The member 8 is caused to rotate or oscillate by the movement of the float 5 communicated by the connections 6 and 7.

The flat portion of the member 8, Figs. 3 and 5, projects into the chamber 14 and the check valve 13 is kept from its seat by the screw 40 threaded in the cover 15. When 90 it is desired to remove the control or alarm valves for repairs, the screw 40 is run back, thereby allowing the internal pressure to force the check valve 13 to its seat thus preventing the escape of steam while the water 95 column is still in service, as in my former patent. To insure the firm seating of the check valve 13, I use a screw 42 threaded in a thimble 44 screwed in the opposite wall of the space 4, such screw to be used for this 100 purpose when necessary.

Pivoted to the interior of the chamber 14 are levered and weighted cams 37 and 38, Figs. 2 and 3, adapted to engage an upper part of the projecting end of the member 105 8 on opposite sides thereof. Projecting forks on the cams 37 and 38 engage a pin 36 placed at the lower end of a stem having a valve 35 which seats in and controls a suitably formed opening in the plug or 110 nipple 2 carrying an alarm whistle. The weighted cam levers 37 and 38 hold the

whistle valve 35 seated until the check valve member 8 rotates sufficiently in either direction to engage one of the levered cams whereby to draw the valve 35 away from its seat and sound the alarm.

The plug or nipple 2, Fig. 2, is threaded into the wall of the chamber 14 and provided with a lock nut and soft washer, by means of which it may be adjusted and fixed in any required position. Screwing it downwardly will cause the cam levers 37 and 38 to swing apart and allow a relatively great rotary movement of the member 8 before the alarm is sounded. Screwing it upwardly will have the opposite effect. I am thus able to adjust the alarm limit independently of the control feature, which could not be done with the device of my said former patent.

Pivoted to the inner face of the chamber 14 is the lever cam 18 adapted to engage the lower part of the member 8 and communicate motion to the pilot valve stem 19 through the medium of the pin 19² in the forked notch 18³ in the lever cam 18. This cam is made right and left for a purpose hereinafter explained. The valve stem 19 has a valved portion 19' shaped to control an opening in the upper end of the nipple or plug 21. The stem extends down past the lower end of said nipple or plug, and is threaded to receive the piston valve 25 adapted to close the cylindrical opening 26. The distance between the valves 19' and 25 is so adjusted that the opening 26 will be sufficiently uncovered when the valve 19' is closed. The area of the aperture 26 being liberal, but very slight uncovering thereof is sufficient, and a very slight movement of the stem 19 will close it before the valve 19' is entirely open. When the valve 19' is fully open, the valve 25 travels in the opening 26 a definite distance.

Under normal conditions of operation the alarm whistle is not operated for long periods, and it is of great importance to give the piston valve 25 a definite movement in the cylindrical seat 26 under all conditions, for the reason that dirt will accumulate on the unused surfaces of the opening 26, and an occasional exaggerated travel of the valve 25 will cause it to stick in the seat and impair the working of the machine.

In order to prevent the valve 25 from moving to a new or unused position in the seat 26, a definite amount of motion is given to the pilot valve stem 19 as follows: The pivoted lever cam 18 is furnished, Fig. 2, with a notch 18' above the pivot, said notch being flanked by the curved surfaces 18², they having the same radius as the opening 41, but being struck from different centers. The object of this formation is to allow a limited oscillation of the cam 18 sufficient to move the valve stem 19 through

its desired travel, and then allow the member 8 to slide on the curved surface 18² and hold the cam 18 stationary while it (the member 8) makes the necessary further motion to move the weighted cam levers 37 70 and 38 and sound the alarm at any desired distance.

The plug or nipple 21 is similarly threaded into the wall of the chamber 14 and furnished with a lock nut and soft washer in order that it may be adjusted and held in position. When it is screwed up it will raise the level to be maintained, and when screwed down will lower it. I am thus enabled to adjust the water level independently of the alarm devices, as I could not with the combinations found in my said former patent, wherein the two functions were affected by the same member. The advantage of being able to remove the plug 85 21 or the plug 2 with its accompanying parts for regrinding or other repairs while the water column is still in service, is retained by means of the check valve 13 closing upon its seat 12 as in that patent when the screw that holds it normally unseated is backed off.

On the nipple 21 is formed a hexagon having a threaded opening 27 which is located between the valves 19' and 25. Steam 95 is led through a pipe screwed in this opening 27 to the mechanism controlling the feed pump. I provide three holes in this hexagon and plug, two of them for the reason that the adjustment frequently requires less 100 than a whole turn, and one of these holes will point to the desired direction. A union fitting is provided at the outer end of the nipple 21 from which the exhaust is led to a convenient place.

It is frequently necessary to reverse the action of the valves 19' and 25 for right or left hand installations, as well as for other reasons, and to accomplish this I provide another opening 43 in the wall of the 110 chamber 14 into which the nipple 21 may be screwed. The hole not in use is plugged as shown.

For instance, if the closing of a by-pass valve from the feed to the suction of a 115 constantly driven pump, in order to force water to the boiler, is desired, instead of opening the feed valve from an intermittently driven pump, it is only necessary to transfer the nipple 21 with its accompanying 120 parts to the opening 43, and plug the hole from which it is removed. It is obvious that the control of water to a boiler from a constantly driven plunger pump may be accomplished by a by-pass valve 125 from the discharge to the suction, in which case the by-pass valve must open for high water, and close for low water, instead of closing for high water and opening for 130 low water, as is the case when the valve is

in the feed line to the boiler; hence the desirability of this reversing feature. Also, it is sometimes necessary to admit and exhaust pressure alternately to and from opposite sides of a piston actuating a belt shifter or rheostat controlling the pump, in which case I use a nipple 21 in each of the openings at the same time and operate them alternately by means of the above described mechanism, in order to handle a belt shifter or rheostat, the extra hole 43 serving this purpose. By this means I am able to accommodate a standard machine to the widest possible range of external conditions.

The operation is as follows: With the boiler in service, and the water at the desired level, the parts or elements would stand as shown in Fig. 2, the valve 19' being partly open, the valve 25 closed, and pressure going to the diaphragm feed-valve through the opening 27, and stopping the flow of water to the boiler. If the feed-valve were defective or if, for any other reason, the water should continue to rise, the member 8 would rotate its lower part to the left first, giving full opening to the valve 19', and full stroke to the valve 25, and then, its lower edge riding on the curved projection 18² until its upper part strikes the weighted lever cam 38 at the predetermined later point, will effect the sounding of the alarm for high water. If for any reason the water should fall, the member 8 would rotate its lower part to the right allowing the weighted lever cams 37 and 38 to close the whistle port; a further fall to the normal would return the parts to the positions indicated in Fig. 2; a further fall would move the cam 18 so as to close the pilot valve 19' and open the piston valve 25, allowing the pressure in the diaphragm-valve to escape through the opening 26, and start the feed. If for any reason the water should continue to fall the member 8 would rotate until its upper part struck the lever cam 37 so as to cause the sounding of the alarm for low water, and so on.

I claim:

1. The combination in a feed water regulator of an alarm device, an oscillating spindle operated by a float, a pilot valve associated with said spindle, means for moving said pilot valve through a limited space and then holding it stationary while said spindle moves through a larger arc to operate the alarm device.
2. In a feed water regulator furnished with alarm means, a spindle adapted to be oscillated by the rise and fall of the water in the water column, a pilot valve, means for moving said valve through a predetermined distance and holding it stationary while the spindle oscillates through a greater arc to

operate said alarm means at a more or less deferred time.

3. In a feed water regulator furnished with alarm means, a spindle adapted to be oscillated by the rise and fall of the water in the water column, a pilot valve, means for moving said valve through a predetermined distance and holding it stationary while the spindle oscillates through a greater arc.

4. In a feed water regulator, a water column having a float therein and adapted to be connected with a boiler above and below the water line, said column being further provided with an auxiliary chamber forming a part thereof, combined with an independently removable and adjustable plug or nipple having a steam passage and an exhaust passage therein covered by valves and connected with means for controlling the passage of water to a boiler, an independently adjustable and removable plug or nipple having a steam passage therein covered by a valve and connected with means for sounding an alarm, an oscillating and endwise moving valve and stem loosely mounted in a valve seated passage leading from the float chamber and controlled as to oscillation by said float and as to endwise motion by means projecting to the atmosphere and connected to the valves in the plugs or nipples aforesaid by interposed means, said means being adapted to operate the feed controlling valve on the initial oscillation of said valve stem through a definite predetermined distance and to hold it stationary while the oscillation of said valve stem through a larger arc will operate the alarm controlling valve at a more or less deferred period, the construction being such that the endwise movement of said valve stem may be externally controlled to keep its valve from its seat while the device is working, or force it to the seat and shut off the steam from said auxiliary chamber while said nipples with their accompanying valves are removed for repairs.

5. In a feed water regulator the combination of a water column connected with a boiler above and below the water line, an auxiliary chamber secured to said water column and provided with a valve-seated opening connecting it with said water column, and a corresponding main valve and stem loosely journaled in said opening and projecting into both chambers, a float in said water column connected by levers to one end of said main valve and stem whereby said stem is oscillated, means projecting to the atmosphere whereby said stem may be moved endwise to seat or unseat its valve at will, an independently removable and adjustable plug or nipple projecting into said auxiliary chamber and provided with a steam port and an exhaust port covered by valves and connected with means for con-

- 4
- trolling the feed water to a boiler, an independently removable and adjustable plug or nipple projecting into said auxiliary chamber and having a steam port covered by a valve and connected to means for sounding an alarm, means for operating said valves in said nipples from the projecting end of said main valve and stem whereby to cause the feed-controlling valves to move through 5 a definite predetermined distance on the initial oscillating movement of the main valve stem, and then be held stationary while the further rotation of the main valve stem will operate the whistle at a more or 10 less deferred period.
6. In a feed water regulator, a water column having a float therein and adapted to be connected with a boiler above and below the water line, said column being further provided with an auxiliary chamber 20 forming a part thereof, combined with an independently removable and adjustable plug or nipple having a steam passage and an exhaust passage therein covered by valves and connected with means for controlling the passage of water to a boiler, an independently adjustable and removable plug or nipple having a steam passage therein covered by a valve and connected with 25 means for sounding an alarm, an oscillating and endwise moving valve and stem loosely mounted in a valve seated passage leading from the float chamber and controlled as to oscillation by said float and controlled as 30 to endwise motion by means projecting to the atmosphere, said oscillating and endwise moving valve and stem being connected to the valves in the plugs or nipples afore- 35 said by interposed means, said means being 40 adapted to operate the feed controlling valve on the initial oscillation of said valve stem through a definite predetermined distance and to hold it stationary while the oscillation of said valve stem through a larger arc will operate the alarm controlling 45 valve at a more or less deferred period, the construction being such that the endwise movement of said valve stem may be externally controlled to keep its valve from its seat while the device is working, or force it 50 to the seat and shut off the steam from said auxiliary chamber while said nipples with their accompanying valves are removed for cleaning or repairs.
7. In a feed water regulator, a water 55 column 1 having an offset portion 3, a fixture 10 having closable apertures therein, mechanism in said fixture, a nipple adapted to be interchangeably applied to either of said apertures, and mechanism within said 60 nipple adapted to coöperate with the mechanism in said fixture.
8. In a feed water regulator, a water column 1 having an offset portion 3, a fixture 10 having closable apertures therein, mechanism in said fixture, a plug adapted to be applied to one of said apertures, and a nipple adapted to be applied to the other aperture, said plug and nipple being interchangeable, and a mechanism within said 65 nipple, the arrangement being such that the regulator may be used right or left or both right and left simultaneously by substituting another nipple for the aforesaid plug.
- In testimony whereof I affix my signature 70 in presence of two witnesses.
- W. H. BERRY.
